US00D801989S

(12) **United States Design Patent** (10) Patent No.: **US D801,989 S**
Iketsuki et al. (45) Date of Patent: **** Nov. 7, 2017**

(54) **DISPLAY SCREEN WITH GRAPHIC USER INTERFACE**

(71) Applicant: **YOKOGAWA ELECTRIC CORPORATION**, Musashino-shi, Tokyo (JP)

(72) Inventors: **Yuya Iketsuki**, Musashino (JP); **Yusuke Yokota**, Musashino (JP); **Ryuhei Furihata**, Musashino (JP)

(73) Assignee: **Yokogawa Electric Corporation**, Tokyo (JP)

(**) Term: **15 Years**

(21) Appl. No.: **29/582,057**

(22) Filed: **Oct. 25, 2016**

(30) **Foreign Application Priority Data**

Apr. 26, 2016 (JP) 2016-009135

(51) LOC (10) Cl. **14-04**

(52) U.S. Cl.

USPC **D14/485**

(58) **Field of Classification Search**

(57) **CLAIM**

The ornamental design for a display screen with graphical user interface, as shown and described.

DESCRIPTION

The FIGURE is a front view of a display screen with graphical user interface showing our new design.

The broken lines showing an electronic device illustrate environmental subject matter, whereas the broken lines showing a display screen and elements of the graphical user interface including all text, illustrate portions of the article. No subject matter depicted in broken lines form part of the claimed design.

1 Claim, 1 Drawing Sheet
